DELAY DETONATOR

John B. Smith, Frederick R. Seavey, and Carl A. Taylor, Alton, Ill., assignors to Western Cartridge Company, East Alton, Ill., a corporation of Delaware

Application April 5, 1935, Serial No. 14,742

5 Claims. (Cl. 102—10)

This invention relates generally to detonators, and particularly to electrically ignitable detonators of the delay type.

The object of the present invention, generally stated, is to provide an electrically ignitable delay detonator which is positive in operation, even though exposed to moisture, safe to handle and economical to manufacture.

Another object of this invention is to provide an explosive train in a delay detonator wherein the constituents of the charge are so selected and arranged that the detonator will be positive in operation and substantially immune to premature explosions.

15 A further object of this invention is to provide a method of securing the lead conductors in position in an electrically ignitable delay detonator.

Other objects will become apparent to those skilled in the art when the following description is read in connection with the accompanying drawing, in which:

Figure 1 is a view in longitudinal section of a delay detonator constructed in accordance with the present invention;

Figures 2 and 5 inclusive, illustrate respectively the successive steps of the method of securing lead conductors in accordance with the present invention; and

Figure 6 is a detail sectional view of a plug in which the lead conductors are secured.

Figure 7 is a detail view of the end of the lead wire split in accordance with the present invention to receive a resistance bridge.

Figure 8 is a view showing a series of interchangeable delay charges with corresponding interchangeable parts to provide a coordinated gas cooling space.

In accordance with the present invention, generally stated, the explosive train of a detonator of the delay type is composed of a plurality of charges, the constituents of which are so selected that upon ignition of an initial charge the remaining charges will be progressively ignited and burned with a minimum possibility of premature explosion and the maximum practical uniformity. In accordance with the present invention, the constituents of the respective charges are so selected as to secure positive ignition of the next succeeding charge without creating high gas pressures. More specifically the present invention contemplates, in a detonator having a delay charge adapted to burn for a predetermined period of time, a more sensitive charge disposed in position so as to ignite the delay charge ex-

posed to be ignited by the delay charge and in turn to ignite the initiating detonator charge.

The present invention further contemplates a method of securing the lead conductors in the end of a delay detonator whereby the same are not only held positively against relative movement but whereby the arrangement lends itself particularly to water proofing.

Referring now to the drawing, Figure 1 illustrates one embodiment of a detonator construction in accordance with the present invention.

Such a detonator may comprise a tubular housing 1 which may be formed of sheet metal or other suitable material into one end of which a pair of lead conductors 2 extend as shown. The lead conductors which are preferably of the insulated type may have their ends skinned as shown at 3 and about the skinned portion, a plug 4 of hard material such, for instance, as sulphur may be cast. The plug 4 is preferably so proportioned as to be insertable in the end of the tubular housing 1 but to substantially fill the end thereof. The particular method of kinking and mounting the ends of conductors 2 in plug 4 will be more specifically described hereinafter.

Arranged across the ends of lead conductors 2 is a resistance filament 5 adapted to be energized from a suitable source of electrical energy to which the conductors 2 lead and surrounding the intermediate portion of the filament 5 may be a charge 6 of priming material adapted to be ignited by a heated filament.

The priming charge 6 may be of any suitable composition, such, for instance, as the following:

	Per cent	35
Nitro starch	20	
Mercury fulminate	22.5	
Lead sulphocyanate	30	
Potassium chlorate	15	
Ferro silicon	10	40
Charcoal	2.5	

but any other suitable composition may be used.

On the interior of housing 1 and in spaced relation to plug 4 may be a tube 7 of brass or other suitable material arranged to fit snugly within housing 1 and adapted to contain a delay charge or fuse 8. At the end of the delay charge 8 nearest the priming charge 6 may be an ignition charge 9 of more sensitive composition than the delay charge and adapted to be readily ignited by a flame from the primer charge 6. For instance, the ignition charge 9 may be composed of 60% fast black powder and 40% slow fuse powder (such as 200 second) of approximately 55

equal mesh. As pointed out above, however, the delay charge of fuse 8 may be of a less sensitive material but one, the burning rate of which is well known. For instance, such a suitable 5 charge may comprise smokless powder of a suitable type which may, if desired, be blended with a suitable amount of black powder. It will be understood, of course, that the length of the fuse 8 and the loading density may be regulated 10 in accordance with the delay desired for the particular detonator, it being understood that the parts may be made longer or shorter, in order to control the burning period and thereby control the length of the delay.

15 As clearly shown in Figure 1, considerable space is left on the interior of tube 1 between priming charge 6 and ignition charge 9. This intervening space provides expansion space for the gases generated upon combustion of both the 20 priming and ignition charges, as well as the delay charge and thereby reduces the danger of premature explosions. In order to permit the escape of gases generated and thus prevent excessive pressures in the expansion space 10, an opening 25 such as 11 may be formed in the wall of tube 1. The opening 11 may, in accordance with the present invention be covered with a film 12 of suitable water proofing material which is readily disruptable by the pressure set up in space 10.

30 A suitable composition is as follows:

	Per cent
Ethyl acetate	68
Nitrocellulose	17.5
Resin	10
35 Camphor	4.5

but other suitable compositions may be employed.

That portion of housing 1 in which vent 11 is situated may be enclosed within an auxiliary sleeve 13 extending entirely around the housing 1 40 and tightly fitting the latter at both of its ends. The sleeve 13 may be provided with one or more vent openings 14, preferably arranged on the opposite side of the assembly from vent 11, that is to say, in approximate diametrically opposed relation 45 from vent 11. With the vents 11 and 14 thus arranged, it is apparent that gases escaping from vent 11 will be baffled by sleeve 13 and caused to pass around to the opposite side of housing 1 before they may escape through vent 14. Consequently, if any incandescent sparks should escape 50 with the gases through vent 11, they will be caused to travel for sufficient distance in the space between housing 1 and the sleeve 13 to permit them to cool sufficiently that they will not 55 prematurely ignite the charge to be exploded. Moreover, in such relation, the sleeve 13 operates to protect the water proofing film 12 from accidental puncture.

As remarked above, the period of delay may be 60 varied by varying the length of fuse 8 and this may be accomplished by providing a series of tubes 7 of various lengths differing, for instance, as by intervals of approximately one second. In 65 accordance with the present invention, sleeves 13 are coordinated with the delay charge, the longer the delay interval the greater the length of sleeve 13. Accordingly, a series of sleeves 13 differing in 70 length by increments of about one-eighth inch per interval of delay, or, for instance, one corresponding to each length of tube 7 may be provided so that as the period of delay increases the volume of the gas cooling chamber within the sleeve 13 also increases and greater cooling is 75 effected due to the increase of metal surface.

This is clearly illustrated in Figure 8 which shows a series of delay tubes 7, 70 and 71 with their charges and therebeneath a corresponding series of sleeves 13, 30 and 31, the lengths of which are coordinated with the length of the charges in 5 tubes 7, 70 and 71 so as to effect proper cooling of the gases.

Disposed adjacent the end of delay fuse 8 opposite ignition charge 9 is another sensitive charge 15 which may be descriptively termed a 10 flash charge, the composition of which may be such as to be readily ignitable by the delay fuse 8 and which, when ignited generates sufficient heat and/or flame to properly ignite the detonating charge 16 and thereafter the base charge 17 of 15 an ordinary blasting cap having a cartridge 18. Such a flash charge as 15 may, for example, be composed of fast burning black powder which passes 24 mesh and is caught on 46 mesh. The detonating charge 16 may comprise mercury fulminate, trinitrotoluene, picric acid, tetryl, potassium chlorate and the like in various suitable combinations and proportions; but where the device is used as an igniter with blasting powder, the detonating charge may be replaced by black 25 powder. In the embodiment shown in the drawing, the flash charge 15 is disposed in the cartridge of the blasting cap, although it will be apparent that the flash charge 15 might, if desired, be positioned in the end of housing 1 or even in 30 the end of delay tube 7 so as to be ignitable by the delay fuse 8. In the latter case, it will be understood that the end of the delay tube should be sealed with a suitable water proofing.

The open end of the cartridge 18 may, as shown 35 in the drawing, be connected with the adjacent end of housing 1. This connection may be accomplished by telescoping the respective parts, as shown in the drawing and corrugating the same to hold the same in position. When it is 40 desired to employ the corrugation for holding the parts together, the exterior of delay tube 7 may be provided with a circumferential groove 19 into which the metal of the housing 1 and cartridge 18 may be crimped. Moreover, the end 45 of cartridge 18 may be sealed to housing 1 using a suitable water proofing such as that of film 12.

The end of housing 1 opposite the blasting cap or detonator may be suitably sealed after the insertion of plug 4 with the embedded lead wires 3 50 by depositing thereupon a small amount of a suitable water proofing material 20 which may, for instance, be of the following composition:

	Per cent
Pitch	55 60
Rosin	35
Linseed oil	5

Over the layer of water proofing material may be poured sufficient molten sulphur to fill up the 60 end of housing 1 and hold the other parts in position. Such a sulphur filler is designated as 21.

If desired an additional kink may be formed in lead wires 2 so that the kink may be embedded in 65 sulphur filler 21 so as to more firmly hold the wires against relative movement or displacement.

In preparing plugs 4 with the conductors 2 embedded therein, as hereinbefore described, a convenient procedure is illustrated more or less diagrammatically in Figures 2 to 5 inclusive. As shown in Figure 2 the wires 2 may be first provided with kinks 3 and thereafter a suitable hard material, such, for instance, as sulphur may be cast about the same to form plugs 4 as shown in 70 75

- Figure 3 so that the bare ends of conductors 2 extend slightly beyond the end wall of plug 4, as shown at 22. The extending ends 22 of the conductors 2 may then be bridged across by resistance filament 5. This may be accomplished in accordance with the procedure set forth in United States Patent No. 1,605,688 wherein the ends 22 of the lead conductors are first split and a resistance filament swaged in position.
- 10 After the resistance filament 5 has been secured to ends 22 of the lead wires, a suitable moldable substance such, for instance, as sulphur may then be cast about the connections between the filament 5 of the lead wires, as illustrated at 23. The 15 auxiliary plug 23 may be so cast as to bond itself with plug 4 and thus provide a firm support for the entire assembly.

Preferably, the auxiliary plug 23 is so cast that the intermediate portion of filament 5 is left exposed, as shown at 24 in Figure 6. This may be accomplished by providing a recess 25 of suitable configuration in auxiliary plug 25. The recesses 25 may thereafter be filled with the priming mixture 6.

25 From the foregoing description it is apparent that when the filament 5 is energized as by an electric current passing therethrough, the priming charge 6 in which the filament is buried becomes ignited due, either to the rise in temperature of filament 5 or a burning out of the same causing an arc within the primer charge. The flame or flash produced by ignition of the priming charge is then effective to ignite ignition charge 9 which latter, being in contact with the end of the 30 delay charge or fuse 8, ignites the delay charge. The delay charge then continues to burn for a predetermined interval.

The combustion of the ignition charge 9 creates a sufficient volume of gas to disrupt the water 40 proofing film 12 across vent 11 so that the gases from the priming charge 6, ignition charge 9 and delay charge 8 are vented from the space 10 into the annular cavity between the exterior of housing 1 and the interior of sleeve 13. These gases 45 are forced to travel forward for the length of the annular cavity and to travel through 180° in the annular cavity before they are released to the surrounding medium. It will be understood that the length of the path between openings 11 and 14 will vary in accordance with the length of the 50 delay fuse 8 and accordingly, in accordance with the length of the delay tube 7, the longer the delay the longer the travel between openings 11 and 14.

55 The spiral travel of the gases just described, sufficiently cools the gaseous products of combustion that they are incapable of igniting the explosives with which the detonator is employed. As previously described, the sleeve 13 also operates as a baffle and prevents premature ignition of the explosive to be detonated by sparks or hot slag from the detonator.

When the delay charge 8 has burned for the

predetermined interval, the flash charge 15 is ignited and produces a sufficient flash to properly ignite the detonating charge 16.

From the foregoing description, it is apparent that many modifications of the delay detonator hereinbefore described will present themselves to those skilled in the art without departing from the spirit of this invention. It is to be distinctly understood, therefore, that the embodiment hereinbefore specifically described and shown in the drawing, is for illustrative purposes only and that the invention is not limited to the specific details thereof. Such modifications and the use of such individual features and subcombinations of features as do not depart from the spirit of this invention are, although not specifically described herein, contemplated by and within the scope of the appended claims.

Having thus described the invention, what is claimed is:

1. The method of making delay detonator connections comprising, forming kinks in a pair of lead wires, embedding the kinks in a plug of hard material with the ends of the wires extending therebeyond, then connecting a resistance filament to the ends of the wires, and surrounding the connections with hard material bonded to the plug.

2. The method of making delay detonator connections comprising, forming kinks in a pair of lead wires, casting a sulphur plug about the kinked portions of the wires with the ends of the wires extending beyond the plug, splitting the ends of the wires, bridging a resistance filament between the split ends, and thereafter casting additional sulphur about the end portions of the wires and filament and in bonded relation to the plug.

3. A delay detonator comprising in combination, a tubular housing, a series of tubes each containing a delay charge of different lengths and adapted to fit said housing, and sleeves corresponding to each tube of the series, said sleeves arranged to fit over said housing to provide a gas chamber thereabout having a volume depending upon the length of the delay.

4. A delay detonator comprising in combination, a housing having a gas vent, a delay column in said housing, the length of said column depending upon the period of delay desired, and a sleeve about the vented portion of said housing, the size of said sleeve being coordinated with the length of the delay column.

5. A delay detonator comprising in combination, a housing, removable delay charge in said housing and a series of members selectively cooperating with said housing to provide a gas cooling chamber having a volume coordinated with the delay charge.
